UNITED STATES PATENT OFFICE.

ALBERT WILLIAMS DAW AND ZACHARIAS WILLIAMS DAW, OF LONDON, ENGLAND.

VALVE MECHANISM FOR AIR-COMPRESSORS OR THE LIKE.

SPECIFICATION forming part of Letters Patent No. 765,359, dated July 19, 1904.

Application filed July 7, 1902. Serial No. 114,644. (No model.)

To all whom it may concern:

Be it known that we, ALBERT WILLIAMS DAW and ZACHARIAS WILLIAMS DAW, both subjects of the King of Great Britain, residing at 11

5 Queen Victoria street, in the city of London, England, have invented new and useful Improvements in Valve Mechanism for Air-Compressors or the Like, of which the following is a specification.

10 The present invention relates to valve mechanism of the kind described in the specification of the prior patent, No. 679,955, dated August 6, 1901, granted to the above-named Zacharias Williams DAW; and it consists in 15 improvements in the construction of such valves and in the method of operating same to be hereinafter fully described.

We will proceed to describe the application 20 of the invention to air-compressors, and as 20 the construction and also the means of operating the inlet and delivery valves at both ends of the compression-cylinder (when the engine is a double-acting one) are identical a description of the valves at one end of such 25 cylinder will suffice to enable the invention to be fully understood.

In order that such improvements may be 30 fully understood, we will proceed to describe same by the aid of the accompanying drawings, in which—

Figure 1 is a vertical section through one 35 end of the compression-cylinder and the inlet and delivery valves and valve mechanism at such end. Figs. 2, 3, and 4 are vertical sections through the delivery-valve and its actuating mechanism, showing certain modifications of the arrangement illustrated in Fig. 1; Fig. 5, a vertical section through the inlet and delivery valves and valve mechanism, showing 40 a further modification of the arrangement illustrated in Fig. 1; Fig. 6, a plan view of a motor and air-compressor, showing a suitable manner of mechanically actuating the slide valve or valves by which the inlet and delivery 45 valves of such compressor are operated at the required times; and Fig. 7, an end view of the inner face of the delivery-valve. Fig. 8 represents a transverse section showing the connection of the cushioning-cylinders for the

inlet and delivery valves of the compression- 50 cylinder and one form of connected mechanism for actuating the controlling-valve for said cylinder.

The first improvement of the present invention is illustrated in Fig. 1 and consists in 55 the arrangement for controlling the action of the piston 12, mounted on the spindle 9, connected to the delivery-valve 1 of the compressor and serving to approximately balance the difference in the pressures on the two opposite sides of such delivery-valve up to the time when the latter begins to open, and thus avoid any great difference of pressure in the compression-cylinder 2 above that in the receiver. For this purpose instead of connecting 60 the forward end of the cylinder 13, in which the balancing-piston 12 works, with the rear end of the compression-cylinder 2 by a port controlled by the compressor-piston 15, as in the arrangement described in the specification of 65 Patent No. 679,955, dated August 6, 1901, above referred to, a small pipe 18, connected with the passage 40, leading to the receiver, is arranged to convey air therefrom to a valve-chest 46, situated outside the balancing-piston 70 cylinder 13. This valve-chest contains a valve which is actuated mechanically in any suitable manner to alternately open and close communication through said pipe 18 between the passage 40 and the forward end of such 75 cylinder 13. The valve illustrated for this purpose is a slide-valve 47, which when closed permits the cylinder 13 to exhaust through ports 100 and 51. By this means it will be seen that only the small quantity of air in 80 front of the balancing-piston 12 will be exhausted each time the travel of such piston is reversed, as the delivery-valve 1 closes instead, as in the previous patent, of exhausting 85 also the air contained in the passage connecting the small piston-cylinder 13 with the compression-cylinder 2.

In the patent above referred to the balancing-piston cylinder 13 is described as being open at its outer end; but the same effect of 90 balancing the pressures on the two sides of the delivery-valve 1 may be produced by employing a cylinder 13 closed or practically

closed at its rear end and when entirely closed providing any suitable means, such as a slide-valve, for opening such end to the atmosphere and also, if desired, for introducing pressure between the closed end of the cylinder and its piston by throttling the exhaust from such closed end of the cylinder, so as to still further buffer the valve and prevent its too violent opening. One means for partially closing the outer end of cylinder 13 is illustrated in Fig. 1, the partial closing being effected by a sleeve or bush 48 on the piston-rod 9. This sleeve enters the open mouth of the cylinder 13 and is slightly smaller in diameter than the said mouth, so as to leave a certain clearance between the sleeve and the cylinder.

Fig. 2 illustrates an arrangement in which the outer end of cylinder 13 is entirely closed and provided with means for the gradual escape under a cushioning pressure of the air at that end of the cylinder. The slide-valve 47 when in its outward position will through port 50 place the outer end of cylinder 13 open to the exhaust 51; but this valve will only partially open the port 50 and will consequently partially throttle said port, and the air contained in the space between piston 12 and the outer end of cylinder 13 will be confined and only be able to escape gradually through the port 50 to the exhaust-port 51, so that it will exert a certain resistance or pressure upon piston 12 and still further buffer the delivery-valve 1 and prevent its too violent opening. When on the completion of the compression-stroke the delivery-valve, having been opened, is about to close, the front of cylinder 13 will by the movement of slide-valve 47 be opened to exhaust and the port 50 from the rear of such cylinder closed, so that as the air cannot enter behind the piston the pressure in the rear end of the cylinder will be greatly reduced, and so establish a partial vacuum, and thus cause such reduced pressure to act as a dash-pot to prevent the too violent closing of the delivery-valve. It will be readily understood that by constructing the slide-valve 47 so that when in its outward position port 50 will be fully open to exhaust 51 the air will be able to escape freely and practically no buffering action of the delivery-valve will be effected thereby.

According to a modification illustrated in Fig. 3 we may cause the piston 12, controlled by the slide-valve 47, to act as a closing-piston instead of a balancing-piston, as in the arrangement above described, and in this case the piston 7, connected to the delivery-valve 1 and the inner face of which is open to the receiver-pressure, will act as the balancing-piston. In this form the mechanically-operated slide-valve 47, is through the port 50 caused to place the rear of the piston 12, which it controls, alternately open to supply and exhaust while the space in front of same only

serves as a dash-pot by reason of any leakage from the rear to the front of the piston, a small opening 49 being provided, if desired, in the front of the cylinder 13 to allow the motive fluid to gradually escape during the closing stroke of the piston 12. On the other hand, the piston 7, connected directly to the delivery-valve 1, will, as before, be permanently open to receive pressure from the receiver, while its rear end is now permanently open to the atmosphere, (or in successive stage compression to the pressure of the preceding stage,) so that such piston 7 will act as a balancing-piston to the delivery-valve 1. The area of the closing-piston in this case is so proportioned to the area of the balancing-piston as to overcome the full receiver-pressure on such balancing-piston and to allow of a sufficient margin to rapidly close the valve. When the rear of the closing-piston 12 is open to pressure, it will (either alone or with the assistance of a spring 14) overcome the pressure on the front face of the balancing-piston 7 and the weight of the delivery-valve 1, and so close the latter.

According to a further modification the piston 12, controlled by the slide-valve 47, might be caused to serve both as a balancing-piston as well as a closing-piston by causing said slide-valve to also control the supply and exhaust of motive fluid to the front as well as to the rear of such piston. This arrangement is illustrated in Fig. 4 of the accompanying drawings, where it will be seen that the movements of the slide-valve 47 will through the ports 50 and 100 alternately place the rear and front of piston 12 open to supply and to exhaust 51.

A further improvement is illustrated in Fig. 1 and relates to the inlet-valve 23, and same refers to the means whereby the rear end of the cylinder 30, in which the inlet-valve-actuating piston 29 works, is placed open to pressure from the receiver at the required time for actuating such inlet-valve. In the prior patent this is effected by a small slide-valve, the chest of which is in communication with the receiver, and such valve was actuated by means of passages leading from the compression-cylinder to a cylinder in which worked a piston whose spindle also carried the slide-valve, said passages being controlled by the travel of the compression-piston. A pipe led from the valve-chest to the rear of the actuating-valve cylinder and was alternately placed open to pressure in the valve-chest and to exhaust by movements of the slide-valve when actuated.

According to the present improvements the slide-valve 34 is arranged directly upon the actuating-valve cylinder 30 and actuated by any suitable mechanical means. It will be seen that the movements of slide-valve 34 will through the ports 53 and 54 place the rear of the actuating-piston 29 alternately

open to supply and exhaust. The same mechanical means might be employed for actuating the slide-valve 34 of the inlet-valve 23 as are used for actuating the slide-valve 47 of the delivery balancing-piston 12, so that the same means will serve for both purposes. A suitable arrangement for this purpose is illustrated in Fig. 6 of the drawings, where it will be seen that the crank-shaft 55 of the motor 56, which actuates the compressor, carries a helical wheel 57, gearing with a corresponding wheel 57^a on a counter-shaft 58, upon which is mounted a worm 59, engaging a pin 60 on a pivoted lever 61, the opposite end of which engages the space between two collars 61^a upon a rod 62 capable of sliding longitudinally in bearings and having tappets 63 64 and (when the compressor is double-acting) 63^a and 64^a, which actuate other pivoted levers 65 and 65^a, the other ends of which are connected either to the rod of the slide-valve 34 or of the slide-valve 47. The pivots 70 70^a of the levers 65 65^a are mounted to turn in their bearings with such levers and, as shown 25 in Figs. 6 and 8 and in broken lines in Fig. 1, are extended so as to carry another lever 71, (one at each end of the compression-cylinder when the engine is double-acting,) which actuates the slide-valve of the other compressor-valve, (the inlet or delivery valve, as the case 30 may be,) whereby both slide-valves will be simultaneously operated in the manner described by the same mechanism. The lever 71 is secured to the upper end of pivot 70, so 35 as, like lever 65, to turn with the latter. Consequently when the lever 65 is operated by the tappets 63 64, as described, the slide-valve 34 of the inlet-valve will be actuated simultaneously with the slide-valve 47 of the 40 delivery-valve; but as these inlet and delivery valves open in opposite directions the effect will be that one of same will be opened and the other closed, and vice versa. In Fig. 45 the inlet-valves are supposed to be removed, as the single slide-valves for operating the pistons of both the delivery and the inlet valves at opposite ends of the compression-cylinder are supposed to be applied to the cylinder of the piston of the delivery-valves. The valve-chest of slide-valve 34 may 50 be connected either directly with the receiver or, as shown in Fig. 1, by means of pipe 66 through the valve-chest of the delivery balancing-piston 12.

55 By the means above described an economy is effected in the consumption of the compressed air necessary for opening and closing the inlet-valve.

Instead of employing a separate slide-valve 60 34 and 47 and valve-chest for the closing-pistons of the inlet and delivery valves 1 and 23, respectively, a single valve and valve-chest only might be employed and mounted upon the cylinder of either of such closing-pistons, 65 while one or both ends of the cylinder of the

other piston would be connected by a suitable passage or passages with the single valve-chest, the valve in which would control the supply and exhaust to both piston-cylinders. By this means, besides abolishing one slide-valve and valve-chest, the mechanism for operating such extra slide-valve would be done away with. A suitable method of carrying this into effect is illustrated in Fig. 5 of the drawings, in which the single slide-valve 47 70 75 is shown as applied to the cylinder 13 of the balancing or closing piston 12 of delivery-valve 1, while the rear end of cylinder 30 of the closing-piston 29 of inlet-valve 23 is through pipe 66 connected with a port 67, 80 formed in the valve-chest of valve 47, so as to be placed alternately open to supply and to exhaust through port 51, such valve 47 also serving to place the front of piston 12 alternately open to supply and exhaust through 85 port 100.

A further improvement consists in introducing a buffering arrangement on both the delivery and inlet valve spindles 9 and 28, so as to absorb any shock on the closing of such 90 valves 1 and 23, the arrangement which is illustrated in Fig. 1 being the same for both valves and consisting, broadly, in mounting on each of the spindles 9 and 28 a sliding sleeve 68 or 68^a, which is acted upon by the spring 14 or 95 24, which serves to close or in assisting to close the valves 1 and 23, respectively, such sleeve acting in conjunction with fixed buffer-stops 69 or 69^a, Figs. 1 and 6, arranged in any suitable position and with which the 100 sleeve 68 is brought into contact when the valve closes. Another fixed stop 99 on the gland of spindle 28 of inlet-valve 23 acts as a buffer in limiting the forward movement of the sleeve 68^a on the opening of the valve. A 105 buffering arrangement may be employed to prevent a violent jar or shock when the delivery-valve 1 in opening arrives at the limit of its opening movement. Such arrangement may be carried out in various ways—as, for 110 example, by forming a collar or enlargement on any suitable part of the spindle 9, connected to such valve and carrying the closing and balancing pistons 7 and 12, and providing a recess in a fixed part through which the spindle 115 works, so that when the valve opens the collar will enter such recess and imprison air between such collar and the bottom of the recess. Fig. 3 of the drawings illustrates one method of effecting this, in which the collar 72 is 120 formed on the inner end of piston 7 and when the delivery-valve 1 opens is caused to engage the recess 73 in the piston-cylinder 8. Another method of effecting this is that shown in Fig. 2 and which consists in giving sufficient lead to the slide-valve 47, controlling the piston 12, for balancing or for closing (as the case may be) the delivery-valve 1, so as to insure a certain quantity of motive fluid remaining imprisoned behind the piston 12 on its 125 130

backward stroke in its cylinder. It will, however, be readily understood that any other suitable arrangement may be employed for producing the desired buffering effect for the opening movement of said delivery-valve.

The last improvement relates to the formation of the delivery-valve 1 in such a way as to direct the air in an outward direction all round through the delivery-orifice between 10 the air-compressor cylinder and the passage leading to the receiver, so as to prevent or reduce the eddying motion of the air, which diminishes the efficiency of the compressor. This feature of the invention is illustrated in 15 Figs. 1 to 5, inclusive, and Fig. 7 of the drawings, and consists in forming upon the inner face of the valve a surface or surfaces 4, such surfaces, as shown, being concaved from the top backward to the bottom and from near 20 the edges backward toward the face of the valve and projecting inward through the valve-seat opening, so that the air in passing through the latter when the valve is open will impinge and be directed outward round said opening.

25 What we claim as our invention, and desire to secure by Letters Patent, is—

1. The combination of a compression-cylinder, a delivery-valve opening outward therefrom and having its rear face exposed to the 30 pressure in the receiver, a cylinder open at its inner end to the pressure in the receiver, a spindle provided with a piston on its inner end adapted to work in said cylinder, means connecting said piston with said valve, a spring 35 for closing said valve, a second piston mounted on said spindle, a cylinder in which said last-mentioned piston works, a valve governing the supply and exhaust of the cylinder for the second piston, a pipe leading from the receiver to the valve-chest of said governing-valve, and means controlled by said governing-valve for buffering the stroke of the second piston.

2. The combination of a compression-cylinder, a delivery-valve opening outward therefrom and having its rear face exposed to the pressure in the receiver, a cylinder open at its inner end to the pressure in the receiver and at its outer end to the atmosphere, a spindle 50 provided with a piston on its inner end adapted to work in said cylinder, means connecting said piston with said valve, a spring for closing said valve, a second piston mounted on said spindle, a cylinder in which said second piston works, a valve governing the supply and exhaust of the cylinder for the second piston, a pipe leading from the receiver to the valve-chest of said governing-valve, and means for mechanically actuating said valve.

60 3. The combination of a compression-cylinder, a delivery-valve opening outward there-

from and having its rear face exposed to the pressure in the receiver, a minor cylinder open at its inner end to the pressure in the receiver and provided with an annular recess at said 65 end, a piston adapted to work in said cylinder and provided with a collar adapted to enter said recess, and means for connecting said piston with said delivery-valve.

4. The combination of a compression-cylinder, a delivery-valve opening outward therefrom and having its rear face exposed to the pressure in the receiver, a cylinder open at its inner end to the pressure in the receiver, a spindle provided with a piston on its inner 70 end adapted to work in said cylinder, means connecting said piston with said valve, a spring for closing said valve, a second piston mounted on said spindle, a cylinder in which said last-mentioned piston works, a valve governing the supply and exhaust of the cylinder for the second piston, a pipe leading from the receiver to the valve-chest of said governing-valve, a lever for actuating said governing-valve, a slide-rod engaged by said lever, a shaft provided with a worm, a lever engaging 75 said slide-rod and actuated by said worm, and means for driving said worm-shaft.

5. The combination of a compression-cylinder, an inlet-valve opening inward to the compression-cylinder, a delivery-valve opening outward from said compression-cylinder and having its rear face exposed to the pressure in the receiver, pistons connected with such delivery and inlet valves, auxiliary cylinders in 90 which said pistons work, a valve-chest mounted on one of said auxiliary cylinders and connected with said receiver, means for connecting said valve-chest with the other auxiliary cylinder for operating the piston therein, a 95 valve in said valve-chest, and means for mechanically actuating said valve.

6. The combination with the inlet and also the delivery valve of an air-compressor of two valves mounted respectively one upon each of the cylinders of two pistons connected respectively with said inlet and delivery valves and the means for actuating these two valves by a single mechanism consisting in gearing actuated by the motor operating the compressor 105 and of spindles and levers for transmitting the motion of such gearing to a sliding rod and then by tappets and other levers to the valve-spindles, substantially as specified.

In testimony whereof we have signed our 110 names to this specification in the presence of two subscribing witnesses.
